UNITED STATES PATENT OFFICE.

AUGUST H. KRAFT, OF OAKLAND, CALIFORNIA.

DESIGN FOR A CHARM.

47,262.

Specification for Design. Patented Apr. 27, 1915.

Application filed February 6, 1915. Serial No. 6,600. Term of patent 3½ years.

To all whom it may concern:

Be it known that I, AUGUST H. KRAFT, a citizen of the United States, residing at Oakland, in the county of Alameda and State of California, have invented a new, original, and ornamental Design for a Charm, of which the following is a specification, reference being had to the accompanying drawing, forming a part thereof.

The figure is a perspective view of a charm, showing my new design.

I claim:

The ornamental design for a charm, as shown.

AUGUST H. KRAFT.

Witnesses:

W. A. ANDREWS,
CURT C. DARROW.
